US0D1038931S

(12) **United States Design Patent** (10) **Patent No.:** **US D1,038,931 S**
(45) **Date of Patent:** **** Aug. 13, 2024**

(54) **PORTABLE MONITOR**

(71) Applicant: **Ekleer Co., Ltd.**, Seongnam-si (KR)

(72) Inventor: **Yoon Ji Chung**, Seongnam-si (KR)

(73) Assignee: **Ekleer Co., Ltd.**, Seongnam (KR)

(**) Term: **15 Years**

(21) Appl. No.: **35/518,192**

(22) Filed: **Sep. 1, 2022**

(80) **Hague Agreement Data**

Int. Filing Date: **Sep. 1, 2022**

Int. Reg. No.: **DM/223951**

Int. Reg. Date: **Sep. 1, 2022**

Int. Reg. Pub. Date: **Sep. 1, 2023**

(30) **Foreign Application Priority Data**

(57) **CLAIM**

The ornamental design for a portable monitor, as shown and described.

DESCRIPTION

1. Portable monitor

1.1 : Perspective

1.2 : Front

1.3 : Back

1.4 : Left

1.5 : Right

1.6 : Top

1.7 : Bottom

1.8 : Rear perspective

1.9 : Perspective

1.10 : Front

1.11 : Back

1.12 : Left

1.13 : Right

1.14 : Top

1.15 : Bottom

1.16 : Rear perspective

1.17 : Rear perspective (vertical)

(Continued)

This design is designed to open and close the rear stand; drawings 1.1 to 1.8 show the closed state; drawings 1.9 to 1.17 show the open state.
